UNITED STATES PATENT OFFICE.

GEORGE B. McCACKEN, OF WILLIMANTIC, CONNECTICUT.

REAMER.

Application filed March 16, 1920. Serial No. 366,293.

To all whom it may concern:

Be it known that I, GEORGE B. McCACKEN, a citizen of the United States, and a resident of Willimantic, in the county of 5 Windham and State of Connecticut, have invented new and Improved Reamers, of which the following is a specification.

My invention relates to the class of tools employed for cutting operations in holes 10 previously formed, and an object of my invention, among others, is to provide a tool of this class that shall be extremely strong in its construction and effective in its operation.

15 One form of reamer embodying my invention and in the construction and use of which the objects herein set out, as well as others, may be attained, is illustrated in the accompanying drawings, in which—

20 Figure 1 is a side view of a reamer embodying my invention.

Figure 2 is a view in central longitudinal section through the same.

Figure 3 is a view in cross section on 25 plane denoted by dotted line 3—3 of Figure 2.

Figure 4 is a view in cross section on plane denoted by dotted line 4—4 of Figure 2.

30 My improved reamer comprises a body formed with a cylindrical micrometer bearing 5 and an angularly shaped end 6 by means of which the device may be turned as with a wrench, said body also including 35 a threaded portion 7 for a feeding sleeve, a grooved portion 8 for the cutting blades and a rounded end 9 having a threaded portion 10 for a locking sleeve 11. This body is formed from a single piece of metal, and 40 the formation thereof is such as to provide an extremely strong device.

Grooves 12 are formed in the side of the body extending lengthwise thereof, and cutters 13 are located in these grooves. The cutters and grooves are so formed that the edges 45 of the former will be moved radially in the body as they are moved longitudinally in said grooves, in the construction herein shown, the grooves increasing in depth from 50 one end to the other and the cutters also being wider at one end than at the other. The bottoms of the grooves and the backs of the cutters are so formed that the latter rest 55 squarely on the bottoms of the former for the entire length of the cutters.

An interiorly threaded feeding sleeve 14

is mounted on the feeding thread 7 on the body, the thread within the sleeve being located at a substantial distance from each end thereof, thereby reducing to a minimum the 60 liability of dirt and grit gaining access to said threaded portion and thereby affecting the smooth working of the parts. As a further safeguard against this entrance of dust and dirt the sleeve is made to closely fit the 65 body of the reamer between said thread and the cutters, and it also fits the ends of the cutters, the latter preventing entrance of matter into the grooves 8 underneath the sleeve. As a preventive against the entrance 70 of dust and dirt at the opposite end of said sleeve, the latter is made to closely fit and have a bearing upon a micrometer base 15 that is in the form of a sleeve adjustably mounted on the body and secured as by 75 means of screws 16. This location of the threads at a substantial distance from both ends of the sleeve 14 also prevents any liability to injury of such threads by forcible contact with other objects, the threads being 80 so positioned that they will never be exposed in the regular uses intended for the device. The feeding end of the sleeve 14 abuts against the cutters, the contacting surfaces of the cutters and sleeve being prefer- 85 ably beveled for the purpose of imparting feeding movement to the cutters, and the opposite end of said sleeve is provided with micrometer graduations 17 by means of which the degree of movement of the sleeve, 90 and hence of the cutters, may be determined, a base line 18 on the micrometer base 15 being employed to determine the amount of rotation imparted to said sleeve, and the line 18 may have graduations 19 extending along 95 its length, if desired, and as shown in Figure 1 of the drawings. The sleeve 15 may be adjusted to any position so that the base line thereon will register with the zero reading of the micrometer scale on the feeding 100 and micrometer sleeve 14. This combined feeding and micrometer sleeve is extremely long and has a good substantial bearing, being firmly supported at each end and for a substantial part of its entire length. An 105 interiorly threaded locking sleeve is fitted upon the thread 10, these threaded parts also being located well within the sleeve and at a substantial distance from each end thereof, with the advantages hereinabove set out 110 with respect to the sleeve 14. The end of this sleeve abuts against the ends of the cut-

ters and it is employed to lock the cutters in place after they have been positioned by means of the feeding sleeve 14, both of said sleeves being undercut to receive the cutters 5 and retain them in their grooves.

I claim—

1. A cutting implement comprising a body with lengthwise grooves therein, cutters located in said grooves, a locking sleeve for 10 said cutters, and a one piece feeding sleeve for said cutters, said sleeve having a close contact bearing on its interior surface at each end thereof and at a substantial distance from each end thereof and fitting a 15 threaded portion of the body, said threaded portion of the body being of a length substantially less than the length of said sleeve.

2. A cutting implement comprising a body having lengthwise grooves therein and a 20 feeding thread and a locking thread, cutters located in said grooves, a one piece feeding sleeve fitting one of said threads on the body and surrounding and covering said grooves and having a close contact bearing on its in- 25 terior surface at each end thereof, said sleeve having a threaded portion located at a substantial distance from each end thereof and said sleeve being substantially longer than the threaded portion of said body, a lock- 30 ing sleeve having an interior thread terminating at a substantial distance from each end thereof, said sleeve being substantially

longer than the thread on the body which it fits, said body projecting through and out at the end of the feeding sleeve and having a 35 bearing for said sleeve which sleeve is of a size to provide a space between said thread and said bearing.

3. A cutting implement comprising a body having lengthwise grooves therein and a 40 feeding thread and a locking thread, cutters located in said grooves, a feeding sleeve and a locking sleeve fitting one of said threaded parts on the body, said body extending through and out at the end of said feeding 45 sleeve, a base sleeve mounted upon said body and projecting into the end of the feeding sleeve to form a bearing therefor, and means for securing the base sleeve in place.

4. A cutting implement comprising a body 50 having lengthwise grooves therein and a locking thread and a feeding thread thereon, cutters located in said grooves, a locking sleeve fitting said locking thread, a feeding sleeve fitting said feeding thread and of 55 a length substantially longer than said thread, said feeding sleeve having a bearing at one side of said thread, and a base sleeve projecting into the feeding sleeve on the opposite side of said thread, said base sleeve 60 forming a bearing for one end of the feeding sleeve.

GEORGE B. McCACKEN.
